Primary Examiner — Selina Sikder*(74) Attorney, Agent, or Firm* — Dickinson Wright PLLC(57) **CLAIM**

The ornamental design for a switch with nightlight, as shown and described.

DESCRIPTION

FIG. 1 is a perspective view of the switch with nightlight of the invention;

FIG. 2 is a top view of the switch with nightlight of FIG. 1; FIG. 3 is a right side view of the switch with nightlight of FIG. 1;

FIG. 4 is a left side view of the switch with nightlight of FIG. 1;

FIG. 5 is a rear view of the switch with nightlight of FIG. 1; and,

FIG. 6 is a front view of the switch with nightlight of FIG. 1.

The broken lines showing the switch with nightlight is for the purpose of illustrating the environmental structure and forms no part of the claimed design.
